UNITED STATES PATENT OFFICE.

SAMUEL LIONEL JEFFERIES, OF GAFFNEY, SOUTH CAROLINA.

DENTAL CASTING MACHINE.

Application filed March 14, 1924. Serial No. 699,323.

This invention relates to an improvement in dental casting machines, and has for its object to provide a machine of this character which is so constituted as to permit of the 5 convenient application of the proper degree and character of heat to the various portions of the mold whereby the invention is adapted to conveniently and effectively carry out all of the diversified operations involved in 10 dental casting such as soldering, slowly heating the investment material, burning out the wax, soldering bridges, making small castings such as inlays, fillings, clasps or the like or making large castings such as cast plates, 15 bridges or the like.

A further object is to provide a machine having the foregoing enumerated advantages and capacities and which is also of simple and durable construction, reliable and efficient and convenient in operation and easy and comparatively inexpensive to manufacture.

Other objects and advantages of the invention reside in certain novel features of 25 the construction, combination and arrangement of parts which will be hereinafter more fully described and particularly pointed out in the appended claims, reference being had to the accompanying drawings forming part 30 of this specification, and in which:

Figure 1 is a perspective view, showing one embodiment of the invention;

Figure 2 is a plan view, showing another form of casting lid from that illustrated in 35 Figure 1;

Figure 3 is a view in section on line 3—3 of Figure 2;

Figure 4 is a plan view of a third form of casting lid;

Figure 5 is a view in section on line 5—5 of Figure 4;

Figure 6 is a plan view of a fourth form of casting lid;

Figure 7 is a view in section on line 7—7 of Figure 6;

Figure 8 is a plan view of a fifth form of casting lid;

Figure 9 is a view in section on line 9—9 of Figure 8;

Figure 10 is a view, partly in top plan and partly in horizontal section, showing a slightly different means for supporting the casting table on the standard;

Figure 11 is a view, partly in elevation 55 and partly in vertical section, showing a slightly modified form of standard;

Figure 12 is a fragmentary view of the upper part of the standard shown in Figure 11 and illustrating a different form of casting cup applied to said standard; and 60

Figure 13 is a view in horizontal section on line 13—13 of Figure 11.

Referring to the drawings and more particularly to Figure 1, the numeral 1 designates a base. A standard 2 upstands from the base, and has its lower end releasably secured thereto. A casting table 3 is provided and is supported for vertical adjustment on the base 1 and standard 2 by means of vertical adjustable legs 4 and an adjustable connection 5 on the standard 2. Each leg 4 includes a screw threaded rod 6 secured at its upper end to the table 3 and having an internally threaded sleeve 7 engaged therewith. The lower end of each sleeve 7 is fitted in a socket or seat 8 provided therefor in the base 1. The connection 5 includes a guide 9 integrally formed with the table 3 and slidably embracing the standard 2 and also includes a thumb screw 10 carried by the guide 9 and engageable with the standard 2. In Figure 1 the guide 9 is shown as of rectangular form and being integral with the table 3. In Figure 10 a slight variation of this structure is shown and comprises a stud 11 integrally formed with the table 3 and adapted to be selectively inserted in any one of a series of openings 12 provided in the standard 2. The stud 11 is threaded, as at 13 and the threaded portion 80 projects beyond the rear side of the standard 2 and has threaded thereon a nut 14 whereby the stud is held to the standard. The casting tables 3 are formed with a circular opening 15 with which any one of a set or series 85 of casting lids now to be described are operable. It is to be understood that the casting lids provide for a regulation and control of the degree and character of the heat applied to the casting rings or cups as will 90 hereinafter more fully appear.

In Figure 1 a casting lid 16 is shown fitted in the opening 15 in the table 3. This casting lid 16 is formed with a peripheral flange 17 which fits on the portion of the table 3 95 surrounding the opening 15 to support the lid 16 in the opening. The body portion of the lid 16 is formed with a small seat 18 for the small casting rings and a large seat 19 for the larger casting rings, the seats 18 and 19 taking the form of concentric depressions or recesses in the lid and the 100 105 110

seat 18 being deeper than the seat 19 and being centrally disposed. The casting lid 16 is provided with a plurality of openings 20 which extend entirely therethrough and these openings are so located on the casting lid as to occur in the seat 18 as well as in the seat 19. This plurality of holes admit the heat gradually from the flame directly underneath the mold. The lid 16 is also provided with sockets 21 designed to cooperate with a lifter, such as an ordinary stove lifter, whereby the lid 16 may be conveniently handled. This casting lid 16 may be advantageously used in the initial stages 15 of the casting operation when it is desirable to gradually heat up the mold and drive off the water contained in the investment material thereby safeguarding against the formation of steam in the investment material 20 and consequently against the danger of the steam blowing out the investment material. The use of this lid 16 also prevents excessive expansion and contraction of the mold material and provides for the slow and 25 gradual burning out of the wax. However after the mold has been slowly heated up without danger of excessive expansion of mold material and after the water contained in the investment material has been driven 30 off without danger of the formation of steam, by means of the casting lid 16, then some of the other casting lids hereinafter to be described may perhaps be more conveniently utilized to burn out the wax and 35 complete the casting operation as will be hereinafter more fully set forth, it being understood that all of the casting lids are interchangeable.

In Figures 2 and 3 a second form of casting lid is shown and is designated generally at 22. The casting lid 22 has a peripheral flange 23 corresponding to the flange 17 of the lid 16 and designed to support the casting lid 22 in the opening 15 of the table 3. The casting lid 22 is formed with recesses 24 and 25 defining seats for the casting cups but the perforations are omitted so that a solid casting lid is obtained. This casting lid 22 is designed for use where it is desirable to keep the flame out of contact with the mold and where a very moderate application of heat is desired, and it is provided with sockets 26 corresponding to the sockets 21 in the lid 16.

In Figures 4 and 5 a casting lid, designated generally at 27, is provided and includes as in the other embodiments a peripheral supporting flange 28 and sockets 29 for the lifter. The body portion of the lid 27 is cut away to provide five grid fingers 30 so that this casting lid 27 provides for the application of flame directly to the bottom and sides of the mold and consequently for the application of a high degree of heat. In Figures 6 and 7 a casting lid, desig-

nated generally at 31 is provided and corresponds in all respects to the casting lid 27 except that only four grid fingers are provided, these grid fingers being designated at 32 and the other end of each grid finger 70 is notched, as at 33, to provide seats for lugs 34 carried by a casting ring 35. Thus the casting lid 31 like the casting lids 16 and 22 is formed with a seat for the casting ring.

In Figures 8 and 9 a casting lid, designated generally at 36 is provided and is identical in all respects with the casting lids 27 and 31 except that six grid fingers, designated at 37 are provided and that the upper portions of the outer ends of these fingers are cut away or recessed, as at 38, to provide a seat for the annular flange 39 provided on a casting ring 40.

Obviously the casting lids 27, 31 and 36 are all adapted for use where it is desired to apply a high degree of heat directly to the bottom or lower portion and sides of the casting ring or mold and these three casting lids differ from each other only in the number of grid fingers provided and in the means employed for supporting the casting rings thereon. These lids 27, 31 and 36 may be conveniently employed for completing the casting operation. By using these lids and applying the flame directly to the bottom and sides of the mold or casting ring carried thereby through the opening 15 in the table 3 the gold will not be chilled off but will flow into all the margins, corners and undercuts and completely fill the mold cavity to produce a perfect casting. It is to be understood that the base 1 supports the burner below the casting lids and that the flame of such burner is applied through the casting lid to the lower portion or lower end of the casting ring and the mold carried therein. The casting lids are all interchangeable and may be readily changed so that at all times during the casting operation the degree and character of the heat applied to the lower portion of the mold may be controlled and regulated by means of these casting lids.

The upper end of the standard 2 is bifurcated to provide vertically arranged and spaced parallel arms 41 having series of alined pivot openings 42. An operating lever 43 is provided and is adapted to be fulcrumed in any pair of alined openings 42 by means of a pivot pin 44 selectively cooperable with the alined openings 42 and extending of course through a pivot opening in the lever 43. One end of the lever is formed to constitute a handle 45 and the opposite end of the lever is connected, as at 46, to a retractile coil spring 47 the lower end of which is connected, as at 48, to the base 1. Intermediate its ends the lever 43 carries a casting cup 49 designed to contain moldine,

soft white paper, clay or other soft and pliable material and to utilize this material in coating with the casting rings to force the gold into the mold cavity. In lieu of the cup 49, a cup designed for the use of compressed air and somewhat similar to that shown in Figure 3 of Patent No. 1,464,657 may be employed, the two cups being adapted for use interchangeably. The spring 47 is tensioned to throw the lever 43 to such position as to maintain the casting cup 49 elevated and spaced from the casting ring carried on the lid of the casting table.

In Figures 11 and 13 a slightly modified form of the invention is shown, and consists of a base 50 above which a casting table 51 is adjustably supported by means of adjustable legs 52 identical with the legs 4 of Figure 1 and an adjustable connection, designated generally at 53, on a standard, designated generally at 54. The standard 54 includes a cylinder 55 having its lower end closed, as at 56, and threaded onto the base, as at 57. The upper end of the cylinder 55 is open and a vertically adjustable member 58 is fitted into the cylinder through the opening in the upper end thereof. A collar 59 is fixed to the lower end of the member 58 and coacts with an annular cap nut 60 screwed onto the upper end of the cylinder 55 to prevent the member 58 from being entirely withdrawn from the cylinder 55. The member 58 is however vertically adjustable in the cylinder 55. A compression coil spring 61 is interposed between the lower end of the member 58 and the closed end 56 of the cylinder 55 and tends to elevate the member 58. The connection 53 includes a guide 62 which has a sliding fit on the cylinder 55 and is held in adjusted position thereon by means of a set screw 63 carried by the guide and engageable with the cylinder 55. A casting cup 64 is provided and is mounted on the member 58 by means of an arm 65 having threaded connection, as at 66 with the mem-

ber 58. A handle 67 is fixed to the upper end of the member 58. In lieu of the handle 67 a knob formed upon or connected to the upper end of the member 58 may be employed. It is to be understood that the casting table 51 has an opening into which any one of the casting lids 16, 22, 27, 31, 36 or 152 may be interchangeably fitted and these lids carry the casting rings. The cup 64 carries moldine, soft white paper, clay or other soft pliable material and when the handle 67 is pressed downwardly the member 58 moves downwardly into the cylinder 55 and the cup 64 is brought down onto the ring and mold to force the gold into the mold cavity.

In lieu of using a casting cup such as shown in Figure 11 the arrangement shown in Figure 12 may be employed and the moldine or the like replaced in its action by compressed air. In Figure 12 the numeral 68 designates a casting cup which is mounted on the member 58 by an arm 69 having threaded connection with the member 58. It will be understood that the cups 64 and 68 are interchangeable. An air supply pipe 70 is carried by the cup 68 and extends through the arms 69 and projects beyond the same in order that it may be conveniently coupled to an air supply pipe 71 leading to any source of supply of compressed air.

I claim:

1. In a dental casting machine, a casting lid having a recess providing a seat and adapted to receive a casting ring, said lid having grid fingers, and a casting ring having a flange engageable with said fingers.
2. In a dental casting machine, a casting lid having a recess providing a seat and adapted to receive a casting ring, said lid having grid fingers, the outer ends of the grid fingers being partially cut away at the top, and a casting ring having a flange engageable with the cut away portions of the fingers.

SAMUEL LIONEL JEFFERIES.
